COVER FOR MAGNETIC RECORDING HEADS OR SIMILAR ARTICLE

Henry Dreyfuss, South Pasadena, Calif., assignor to Minneapolis-Honeywell Regulator Company, Minneapolis, Minn., a corporation of Delaware

Filed Aug. 12, 1960, Ser. No. 61,711

Term of patent 14 years

(Cl. D26—14)

FIG. 2

FIG. 1 is a front perspective view of a cover for magnetic recording heads or similar article showing my new design.

FIG. 2 is a cross-section of the design shown in FIG. 1 taken along line 2—2.

I claim:

The ornamental design for a cover for magnetic recording heads or similar article, substantially as shown.
